UNITED STATES PATENT OFFICE.

JAMES FENTRESS, OF CHICAGO, ILLINOIS, ASSIGNOR TO CHICAGO TUBING & BRAIDING COMPANY, OF CHICAGO, ILLINOIS, A CORPORATION OF ILLINOIS.

HOOK FOR FORMING STEEL TUBING.

Application filed June 22, 1922. Serial No. 570,091.

This invention relates to machines for making spirally wound metallic tubing, well known in the art for many uses: among them, a flexible gas pipe between a wall fixture and a lamp on a table, or the like. Such a tube is shown as 10 in Figures 1, 2 and 5 and in cross section in Figure 4.

In the particular kind of tube shown in the drawings, a metal strip 12, of which the tube is formed, is made in an S-shaped or other cross section, shown in Figure 4 and spirally wound so that adjacent layers or convolutions of tube enclose the rubber packing 14, clearly shown in Figure 4, to render it gas and liquid tight. It is extremely difficult to wind spirally such a tube by merely taking a piece of straight, flat parallel sided metal and passing it into a coiling die which receives it at any angle to the motion of the metal strip as it enters the die, but, as is well understood in the art, the metal strip should before entering the coiling die also be curved in the flat plane of the profiled metal strip to thereby contract one side edge of the strip or stretch the other edge, or both. The prior art discloses numerous examples of coiling or tube forming dies for this purpose which completely enclose the S-shaped metallic ribbon as it is being coiled into tubing.

Such coiling dies work with difficulty and require considerable power to operate, due to the frictional area being maximum. In a coiling die of the fully enclosing type, the metal strip is very liable to stick and jam, because no play is allowed to take care of irregularities of thickness of metal strip or variations in temper. Such a die will bear all strains, first on the right side and then shift to the left, depending on the irregularities of the ribbon, etc. This unbalancing of the strains causes many troubles with such dies. Makers of the metal strip cannot produce perfect strip but demand a variation of 10% on thin strips be allowed them, when 10% is equivalent to 1/1000 inch.

The main object of this invention is to provide a hook or die for putting at least the finishing touches on the lateral bending of the S-shaped strip, and for completely forming the strip into a helically coiled tube in which the hook or die engages only approximately one-half of the width of the metal strip to be formed and coiled, thereby materially reducing the friction encountered

and the power required; making the collection of galvanization or dirt in the die impossible, thereby reducing the diameter of the finished tube, while affording more ready inspection of the operation of the machine as the tube coiling takes place. Another object is to combine in one hook or die means for controlling the metal strip after it has been laterally bent to proper form so as to permit ready insertion of the packing required in most instances for a finished tube.

The invention consists in mechanism capable of attaining the foregoing and other objects; which can be easily and cheaply made; which is satisfactory in use and is not readily liable to get out of order; and in many features and details of construction hereafter more fully set forth in the specification and claims.

Referring to the drawings in which like numerals designate the same parts throughout the several views:

Figure 1 shows a plan and Figure 2 a side view of a machine equipped with mechanism illustrating this invention in its preferred form engaged in the actual production of metal tubing 10.

Figure 3 is an enlarged side view taken on the line 3—3 of Figure 1.

Figure 4 is a sectional plan view on the line 4—4 of Figure 2.

Figure 5 is a detailed side view taken on the irregular line 5—5 of Figure 3.

Figure 6 is a developed plan view of the interior or working face of the die.

Figure 7 is a perspective view of the die or hook mechanism removed from the rest of the device.

Figure 8 is a face view of the hook or die removed from the rest of the machine.

The hook of this invention is shown in connection with the conventional form of machine having profiling wheels (13) adapted to produce and force metal tubing (12) through a solid straight die (16) and around a curved track (18) of any suitable curvature required to turn the metal (12) from the plane of the wheels (13) to the hook plate (20) of this invention, rigidly supported at any desired angle with reference to the original machine by means of a suitable support (22) and detachable securing means, such as lag screws (24) inserted through holes (26) in the plate (20).

Particular attention is called to the fact that in Figure 1, the central axis of the finished tube (10) is not parallel to the path of travel of the metal strip 12, as it goes through the guiding blocks or former (16) adjacent to the profile wheels (13); but is at any desired angle with reference to each other, the length and curvature of the track (18) simply conforming thereto. The hook plate (20) is made by taking a flat bar or sheet of steel of sufficient size to be attachable to the support (22) in the manner described, forming through it a perforation (26^a) whose inside diameter corresponds to the outside diameter of that portion of strip 12 which bears on the inside of said perforation; slitting the front portion of the plate adjacent to the bottom of the perforation (26^a) to form the slot (28); bending the lip portion (29) of the plate below the slot (28) to one side, viz: toward the track (18) in the assembled structure of the drawing, so as to form a tube bending cam surface (30) extending from (e) to (f) in Figure 6; shaping the next 180° (32) of the circumference of perforation (26^a) and represented by the distance (f) to (g) in Figure 6, so that it is a cam which properly bends and forms the metal strip (12) to the final pitch of the finished tube (10) and finally bending the lip portion (33, Figure 7) of the plate immediately above the slot (28) so that the portion of the hook or die (34) from (g) to (h) (Figure 6) has less pitch than portion (32) from (f) to (g) (Figures 6 and 8), the same having the functions hereafter described. The portion e to f is also a trackway leading to the main cam, f—g, and portion g—h is also a trackway leading from the main cam.

As indicated in the above paragraph, cam surface (30) merely takes metal strip (12) as it comes from track (18) and bends it in general in conformity with the curvature of track (18) until the metal strip reaches cam portion (32) which is so shaped and designed that it imparts the final spiral to the finished tube (10) and delivers it to cam portion (34) which is, as shown in Figure 6, at a less pronounced pitch than the cam (32), so that the tube (10) formed and pitched by the cam member (32) is forced to take a less pitch as it is guided back along cam (34) from (g) to (h) (Figure 6). The effect is, as shown in Figures 1, 2 and 5, to give a ready clearance space between adjacent interfitting parts of the metal strip, so that the rubber packing 14 can be fed into place with ample clearance space (36) (Figure 4) while the rubber is going into place. As soon as the finished tube (10) passes out of the control of cam portion (34), the natural spring in the metal strip (12) causes it to return to the position defined by the cam portion (32)

with the result that the final tube is produced, as shown in the right hand half of Figure 4, with the rubber packing (14) firmly gripped between four compressing flanges of the metal strip. In other words, the cam surface (32) puts such a decided pitch in the metal strip (12) that it would, if left to itself, travel in the path designated in dotted line (40) of Figure 8, but it is forced because of the necessity of the presence of the rubber packing (14) to lie in the position indicated by the dotted lines (42) of Figure 8.

As the product of the mechanism is a metal cylinder of tube strip 12 emerging at right angles from plate 20, it is highly desirable, if not necessary, that all points on the interior circumferential surface e to h of the perforation through the plate include the parallel surface lines of an imaginary cylinder, co-axial with tube cylinder 12, passing through the plate at said perforation.

In Figure 6, the angle (a) shows the pitch of cam (32); angle (b) shows the pitch of cam face (34) and angle (c) shows the curvature of cam face (30) which is approximately that of track (18). Particular attention is called to the fact that cam plate or hook (20) only engages and controls one-half of the metal strip (12), the theory being that the tool or hook by actually controlling and crimping this half of the metal strip effectually controls the whole of the cross section of the strip. Owing to the fact of control of the tube by engaging only one-half or less of the metal strip, the die is not nearly as expensive to make as would be one which entirely surrounded all parts of the metal strip; the power to push the metal strip through the die is not nearly as great as would be required to push the complete metal strip through a die which completely enclosed it. In actual practice, the hook of this invention reduces the power required to form a metal tube approximately 50% and reduces the cost of the hook or die about 80% when compared to a die completely enclosing the ribbon on its convex surface.

It is entirely possible, in theory at least, to construct a hook of this invention which will completely control and mold the strip 12 from the position shown in the left hand half of Figures 1 and 2 to the finished tube position; but, in actual practice, it is far better to use a curved track for partially bending or crimping the strip, and to only use the device of this invention for giving the finishing definite final touch to the metal strip as it goes into the final tube.

The hook described is novel in that it is the first device of the kind in which the tube is formed by pushing or pulling it through or around the hook with or without the aid

of a live or dead mandrel in the center of the tube to support the tube in formation; or to assist in propelling the tube through the hook or both. The hook is novel in that it 5 governs only one half of the strip, or less than half, in coiling same into tubing. The hook as shown governs the left half of the strip as in Figure 1, but a similar hook governing the right half of strip would give 10 the result desired. It is almost impossible to accumulate galvanization or dirt in this hook, etc. This results in many advantages in the practical production of tubing which it seems unnecessary to set forth in detail.

15 What I claim is:

1. A hook for laterally bending metal tubing strip of suitable cross section to form a proper tube, the same comprising an initially flat plate of suitable thickness to lie between 20 the walls of one half of the section of the strip, there being through the plate a perforation for finished tubing, and a slit in the plate outward from one point in said perforation so that a tube strip may pass through said slit into and around the perforation and thence out of the slit as described, the plate being laterally bent adjacent to the slit and about the perforation for the purposes set forth.

2. A hook for laterally bending metal tubing strip of S-shaped cross section to form a proper tube, the same comprising an initially flat plate of suitable thickness to lie between the walls of one U-shaped half 35 of the S section of the strip, there being through the plate a perforation for finished tubing, and a slit in the plate outward from one point in said perforation so that a tube strip may pass through said slit into and around the perforation and thence out of the slit as described, the plate being laterally bent adjacent to the slit and about the perforation for the purposes set forth.

3. A hook for laterally bending metal tubing strip of S-shaped cross section to form a proper tube, the same comprising an initially flat plate of suitable thickness to lie between the walls of one U-shaped half of the S section of the strip, there being 40 through the plate a perforation for finished tubing, and a slit in the plate outward from one point in said perforation so that a tube strip may pass through said slit into and around the perforation and thence out of the slit as described, the plate being laterally bent adjacent to the slit and about the perforation, the interior circumference of the perforation including at all points in the laterally bent plate lines lying parallel to 45 each other and in the circumference of an

imaginary cylinder passed through the plate at said perforation, for the purposes set forth.

4. A hook for laterally bending S-shaped tubing strip to form it into a tube, the same comprising an initially flat plate of suitable thickness to lie in one U-shaped space on not more than half of the tubing strip, the same being perforated to receive the tube and then slitted outward at one point in the 50 perforation to the edge of the plate, the lip portions, adjacent to said slit, being bent laterally in opposite directions to form tracks on which tubing may enter and leave the slit, the middle portion of the plate adjacent to the circumference of said perforation being inclined to laterally bend or pitch tubing strip led into and out of said perforation via said tracks and forced to travel around the interior of said perforation.

5. A die or hook for laterally bending metal strip into helical form comprising a relatively thin metal plate, having cut in it a cam track adapted to engage not more than half of the metal tube strip to be formed and 55 provided with guiding means by which such a metal strip may be forced over said cam track surface to laterally bend the entire strip.

6. In a device of the class described, a comparatively thin plate perforated near its middle and bent laterally adjacent to said perforation to form a cam track for laterally bending strip passed around the circumference of said perforation, and trackways 60 leading to said main cam track opening out to opposite sides of the plate for the purposes set forth.

7. In a device of the class described, a comparatively thin plate perforated near its 65 middle and bent laterally adjacent to said perforation to form a cam track for laterally bending strip passed around the circumference of said perforation, and trackways leading to said main cam track opening out 70 to opposite sides of the plate, one of said last mentioned trackways being also a cam of less angularity than the main cam for the purposes set forth.

8. A hook for laterally bending metal tubing strip of suitable cross-section to form a proper tube, the same comprising an initially flat plate of no greater width than the distance between the walls of one half of the section of the strip and cooperating means 75 formed out of said plate itself.

In witness whereof, I have hereunto subscribed my name.

JAMES FENTRESS.
